MECHANISM FOR PRODUCING LOOPED KNOTS IN THREAD-KNOTTING MACHINES

Oscar Kleinschmit and Oskar Müller, Leipzig-Plagwitz, Germany, assignors to Gebrüder Erehmer, Leipzig-Plagwitz, Germany, a German firm

Application September 20, 1930, Serial No. 483,371
In Germany May 17, 1930

11 Claims. (Cl. 112—22)

This invention relates to thread-knotting machines and is more particularly concerned with mechanism for automatically forming safety or non-slipping knots in the applied thread.

5 It is known in the art to use such machines for automatically forming safety-knots in the thread applied to books, pamphlets, cards and the like, and it is also known to use mechanism comprising a combination of thread-looping needles and a self-releasing thread-gripper in order to attain this end.

The object of this invention is to improve the mechanism of such machines in a manner such as to enable them also to produce looped safety-

10 knots.

According to this invention, thread-gripping mechanism is provided whereby the closing thread is automatically looped into the tightening loop of the safety-knot during the formation of the latter.

15 In order that the above description may be better understood the invention is shown in the accompanying drawings embodied by way of example, in a thread-stitching machine adapted to produce safety-knots.

Fig. 1 is a side elevational view of the knot-looping mechanism of a thread-stitching machine showing the thread in the initial stage of safety-knot formation;

20 Fig. 2 is a similar view showing the thread-gripper, after having seized the thread, about to carry it to the right to form the knot.

Fig. 3 shows the safety-knot in the third stage of formation.

25 Fig. 4 is a view of the completed safety-knot.

Figs. 5 and 6 are views of the thread-gripper as used for the formation of a looped safety-knot.

30 Fig. 7 is a view, drawn to a larger scale, of the jaws of such a gripper.

Fig. 8 is a view showing the improved type of gripper drawing the looped end of the thread through the initial loops of a looped safety-knot.

Fig. 9 shows the gripper reversing its stroke 35 in order to carry the looped end to the left, to tighten the knot.

Fig. 10 shows the gripper freeing itself from the thread loop whilst carrying the latter to the left.

40 Fig. 11 is view of the formed looped safety knot.

Fig. 12 shows the complete looped and loop-knotted thread formed by mechanism having three looping needles.

45 Fig. 13 shows the complete looped and loop-

knotted thread formed by mechanism having two needles.

Referring to Figs. 1 and 2, it will be seen that in order to form a safety-knot in the known manner, the thread 1 supplied from the spool is drawn out by the thread guide 2 and successively placed onto the vertically reciprocating hook needles 3, 4, 5. The thread-loop, formed by the needle 3, is made relatively long and then formed into the double loop 7, as shown in Fig. 2, in known manner, by parts A (which here are of no particular interest and are only indicated in the drawings) to enable the gripper 6 to pass therethrough and finally to seize the end of the thread, which has been cut off in the meantime and is hanging in

60 the needle 5. The gripper now pulls the thread along, if need be, through the loop of the needle 4, and on reaching a position sufficiently far to the right of needle 3 so as to enable the end of the thread to slip out of the loop 7, the thread members are pulled tight in a known manner

65 (Fig. 3) to form the knot. In this operation the gripper 6 moves to the left again, throwing over the part 7a of the thread loop 7 in order that the safety-knot shown in Fig. 4 may be formed. For 70 this manipulation, the end of the thread must be held in the gripper very firmly and this is effected by the thread being clamped in the gripper so that it cannot slip off but is gradually pulled outward. In order to prevent slipping of the

75 thread the gripper is shaped so that the thread thereof cannot slip out sideways but is caused to be withdrawn from the mouth of the gripper in a vertically upward direction.

80 The automatic formation of the looped safety-knot shown in Figs. 8 to 11 is rendered possible by the end a of the thread being left of sufficient length, so as not to slip out of the loop b when seized by the gripper and drawn through the loop 7 (Fig. 8). In this case, however, the mouth of 85 the gripper 6 must be so shaped that, in the tightening movement to the left, the closed loop can move out of the mouth of the gripper. This slipping movement of the thread from the mouth of the gripper as the latter advances to the left will be readily seen from Fig. 10.

90 The fixed jaw e of the holding jaws is provided with an oblique groove c (Figs. 5, 6 and 7) into which the knot-closing loop is pulled as the gripper moves to the right after seizing the thread. 95 This loop is thus not situated in the longitudinal vertical plane of the gripper but is inclined thereto. That is to say, the lower extremity of the groove extends to one lateral face of the jaw e so that the loop held in the groove c lies to one

side of the nose or fixed jaw *e* as shown in Fig. 9. If, now, the gripper is moved to the left for tightening the knot (Fig. 9) the point of the former in consequence of the obliquity of the loop, passes 5 behind the latter as shown in Fig. 10. The holding jaw *d* of the gripper mouth is slightly bevelled outwardly so that the loop is caused, by the pulling force thereon, to slide outward and so to slip out of the mouth.

10 By this constructional alteration of the gripper it is possible to enlarge greatly the scope of usefulness of thread-knotting machines. For example, the masses of cards designed for use on festive or like occasions and provided with knotted 15 bows which hitherto had to be tied by hand, can by this means be readily produced in much shorter time.

I claim:

1. A thread-gripper for use in a thread-knotting machine comprising a horizontal reciprocating member, a fixed jaw formed at the forward end of the said member and having a slot formed therein at an oblique angle to the longitudinal vertical plane of the said gripper, and a movable 20 jaw adapted to co-operate with the said fixed jaw.
2. A thread-gripper for a thread-knotting machine, comprising a horizontal reciprocating member, a fixed jaw formed at the forward end of said member having side faces bevelled obliquely to the direction of travel of the said member and a rear face slotted at an oblique angle to the longitudinal vertical plane of the said gripper, and a movable jaw having its front face bevelled 30 at an angle to the fixed jaw and inclined toward a mouth leading to the said jaws.
3. A thread-gripper for a thread-knotting machine, comprising a horizontal, reciprocating member, a fixed jaw formed at the end of the said member and having the lower edge of its rear face rounded, a movable jaw, a guiding member for the 40 said movable jaw recessed at its forward end to form, in association with the fixed jaw, a guiding mouth for the thread.
4. A thread-gripper for use in a thread-knotting machine, comprising a substantially horizontal reciprocating member, a fixed jaw formed at the forward end of said member and having a rear face slotted at an oblique angle to the longitudinal, vertical plane of said gripper, said slot 50 extending laterally to emerge on a lateral face of said member, and a movable jaw associated with said fixed jaw.
5. A thread-gripper for use in a thread-knotting machine, comprising a substantially horizontal reciprocating member, a fixed jaw provided on 55 said member and having the rear face of its lower edge rounded, said face being slotted at an oblique angle to the longitudinal vertical plane of the gripper, a movable jaw associated with said fixed jaw, and a guide for said movable jaw, said 60

guide being shaped at its forward end to form in association with said fixed jaw a thread-guiding opening in one lateral face of said reciprocating member.

6. A thread-gripper for use in a thread-knotting machine, comprising a reciprocatory member having a thread-receiving slot formed therein, the walls of said slot being set at an oblique angle to the longitudinal vertical plane of the gripper, and extending laterally so that said slot opens on a lateral face of said member.

7. A thread-gripper for use in a thread-knotting machine, comprising a reciprocatory member having one extremity formed with side faces bevelled obliquely to the longitudinal direction of travel of said member, said extremity of the member being slotted at an oblique angle to the longitudinal vertical plane of said gripper and extending laterally so that said slot opens on a lateral face of said member to receive the thread.

8. A thread-gripper for use in a thread-knotting machine, comprising a reciprocatory member, and thread-gripping jaws mounted upon said member and adapted for relative displacement, a slot to receive the thread being formed in one of 100 said jaws at an oblique angle to the longitudinal vertical plane of the gripper.

9. A thread-gripper for use in a thread-knotting machine, comprising a reciprocatory member, a thread-gripping jaw mounted upon said member adjacent one extremity thereof, and provided with lateral faces bevelled obliquely in the direction of travel of said member, and a second jaw mounted upon said member and operatively associated with said first jaw, said first jaw having a 110 thread-receiving slot formed therein at an oblique angle to the longitudinal vertical plane of the gripper.

10. A thread-gripper for use in a thread-knotting machine, comprising a reciprocatory member, a fixed thread-engaging jaw positioned at one extremity of said member and having a thread-receiving slot formed therein at an oblique angle to the longitudinal vertical plane of said gripper, and a movable jaw mounted upon said member and operatively associated with said fixed jaw.

11. A thread-gripper for use in a thread-knotting machine, comprising a reciprocatory member, a thread-engaging jaw positioned at one extremity of said member and having a thread-receiving slot formed therein at an oblique angle to the longitudinal vertical plane of said gripper, a second jaw slidably mounted upon said member and operatively associated with said first jaw, and a guiding member for said movable jaw recessed 130 to form in association with the fixed jaw a guiding mouth for the thread.
